UNITED STATES PATENT OFFICE.

JAMES WILLIAM PARKER, OF HARROW, ENGLAND.

AUTOMOBILE PRODUCER-GAS PLANT.

1,420,570.

Specification of Letters Patent. Patented June 20, 1922.

Application filed August 29, 1921. Serial No. 496,662.

To all whom it may concern:

Be it known that I, JAMES WILLIAM PARKER, subject of the King of Great Britain, and resident of Harrow, England, have invented certain new and useful Improvements in Automobile Producer-Gas Plants (for which I have filed an application in Great Britain April 8, 1920, Patent No. 162,899), of which the following is a specification.

10 This invention relates to steam generators for producer gas plants and has for its object a simple form of generator adapted to convert water into steam in the quantity required from time to time without 15 the employment of thermo-dynamically operated valves.

According to this invention a vessel adapted to be supplied with water to a constant level is disposed beneath the firebars of the 20 furnace and a projection or projections from the firebars is or are adapted to project into said vessel and to dip into the water therein.

For the purpose of preventing the ends 25 of the firebars of steam boiler and other furnace grates from burning away it has been proposed to provide therebeneath a trough of water into which dips a rib on the bars and no claim is made to this feature per se.

One form of the invention is illustrated by the accompanying drawings wherein Figure 1 is a central sectional elevation and Figure 2 is a sectional plan on the line 2—2 35 Figure 1.

The form of the invention illustrated is especially adapted for use in connection with a small portable producer gas plant and comprises a furnace *a* lined with refractory material *b* and arranged concentrically within an outer casing *c*, the annular space between the furnace *a* and casing *c* serving to pre-heat and conduct a supply of air entering by an inlet *d* near the top 40 of the casing *c*, to the grate which, as shown, may be constituted by an annulus *e*, a diametral rib *f* and a plurality of bars *g* . . . cast integral. A fire door is arranged in a passage *h* leading to the furnace *a* from 45 the casing *c* just above the grate and a similar ash pit door is provided as at *i* just below said grate. A feed hopper *j* is disposed above the furnace *a* which latter is provided with a gas outlet *k* and a perforated gas 50 screen *l*. A pipe *m*, connected with a source

of supply of water through a float chamber *n* or similar means for automatically regulating the flow of water to said pipe *m*, is disposed horizontally below and transversely of the firebars *g* . . . of the furnace *a* and 55 the upper part of said pipe is slotted in the direction of its length as at *o*. Beneath the rib *f* the grate is provided with a downwardly directed tongue or fin *p* lying in the central transverse plane thereof, said tongue or fin *p* being adapted to project into the slot *o* in the pipe *m* and to be a loose fit therein so as to leave a narrow gap for the escape 60 of steam from said pipe. Preferably the tongue or fin *p* is narrower than the rib *f* so as to project at either side and be adapted to 65 overlie the gap just mentioned so as to prevent the entrance of ash or dust to the pipe *m*.

In use a supply of water is maintained 70 in the pipe *m* at a predetermined level and is heated partly by radiation from the fire supported by the firebars *g* . . . and chiefly by conduction through the tongue or fin *p* the greater the intensity of heat of the fire 75 80 the greater the conduction to the water so that steam is generated in the required volume and escapes by the gaps between the fin *p* and slot *o*, the water level being automatically maintained without the employment 85 of any thermodynamically operated valve.

Consequently the plant may be very cheaply and readily produced and there are no parts likely to get out of order.

In some cases the fire bars *g* . . . instead of constituting parts of an integral casting may be formed individually and shouldered as usual at their ends and adapted to be supported by transverse bearing members, 90 said shouldered ends serving also to space apart said bars. Some or all of the fire bars may be formed each centrally of its length with a down-wardly directed transverse tongue or fin adapted to project into the slot *o* mentioned above. If desired the pipe *m* instead of being slotted in the direction of its length as at *o* may be slotted transversely of its length at predetermined positions, some or all of the firebars *g* . . . in such case, 100 being formed each centrally of its length with a downwardly directed tongue or fin lying in the central longitudinal plane thereof, said tongue or fin being adapted to project into a transverse slot in the pipe *m*. 110

Preferably each of such firebars is also formed at either side with an arcuate lateral flange adapted to overlie the gaps between the transverse slots and the tongues or fins so as to prevent the entrance of ash or dust to the pipe *m*.

As many firebars as desired may be formed with the downwardly directed fins, the pipe being correspondingly slotted.

10 What I claim is:—

1. A steam generator for automobile producer gas plants comprising a vessel adapted to be supplied with water to a constant level and disposed beneath the firebars of the furnace, a projection from said firebars adapted to project into said vessel and to dip into water therein.

2. A steam generator for automobile producer gas plants comprising a longitudinally slotted pipe adapted to be supplied with water to a constant level and disposed be-

neath the grate from which depends a single tongue arranged transversely of the firebars and dips into the water in said slotted pipe.

3. A steam generator for automobile producer gas plants wherein some of the firebars are provided with depending tongues adapted to project through apertures in a slotted pipe disposed beneath the grate and means for maintaining a constant level of water within said slotted pipe.

4. A steam generator for automobile producer gas plants comprising a pipe adapted to be supplied with water to a constant level and disposed beneath the grate said pipe being slotted transversely and the grate being provided with depending tongues that are arranged each in the central longitudinal plane of the respective fire bar of said grate and dip into the water in said slotted pipe.

In testimony whereof I affix my signature.

JAMES WILLIAM PARKER.
